US00D777753S

(12) **United States Design Patent** (10) **Patent No.:** **US D777,753 S**
Matsuguma et al. (45) **Date of Patent:** **** Jan. 31, 2017**

(54) **DISPLAY SCREEN WITH GRAPHICAL USER INTERFACE**

(71) Applicant: **ESPEC CORP.**, Osaka-shi, Osaka (JP)

(72) Inventors: **Osamu Matsuguma**, Osaka (JP);
Yasushi Watanabe, Osaka (JP)

(73) Assignee: **ESPEC CORP.**, Osaka-shi (JP)

(**) Term: **15 Years**

(21) Appl. No.: **29/526,747**

(22) Filed: **May 13, 2015**

(30) **Foreign Application Priority Data**

Nov. 14, 2014 (JP) 2014-025405

(51) **LOC (10) Cl.** **14-04**

(52) **U.S. Cl.**

USPC **D14/486**

(58) **Field of Classification Search**

USPC **D14/485-487**

(57) **CLAIM**

The ornamental design for a display screen with graphical user interface, as shown and described.

DESCRIPTION

The FIGURE is a front view of a display screen with graphical user interface.

The outermost dash, dash broken lines in the FIGURE show a display screen and forms no part of the claimed design. The innermost dot, dash broken line in the FIGURE represent a boundary that forms no part of the claimed design.
